RAZOR

Hyman Schwartz, Los Angeles, Calif.

Application March 10, 1944, Serial No. 525,845

6 Claims. (Cl. 30—41)

This invention has to do with a razor and it is a general object of the invention to provide a razor construction that is simple, inexpensive, and practical and which serves to materially improve the efficiency and action of the device.

Razors of the general type commonly known as safety razors are characterized by a frame or holder, which carries a blade and, in use, the razor is drawn over a surface of the skin that has been lathered with the result that the blade engages the beard and removes it. The blade holding frame is usually designed to give reasonable support and to shield the cutting edge of the blade and at the same time shed, as far as possible, the hair that is cut by the blade. In practice the shedding action of the ordinary razor is not satisfactory, with the result that after a very limited use of the razor it is necessary to wash it out in order to dislodge the cut hair. This may be required a number of times in the course of one use of the razor.

It is a general object of my present invention to provide a razor construction which operates to effectively shave without becoming clogged with the cut hair in the manner characteristic of ordinary safety razors. With the construction of the present invention the razor will operate for a considerable length of time without accumulating cuttings in a manner to impair or interfere with the proper action of the blade. Since the construction of the present invention does not become clogged with hair or cuttings it will operate for a considerable period of time without the necessity of washing it or cleaning it, and thus it serves to materially save time and the inconvenience incidental to frequent washing.

Another object of my invention is to provide a razor construction wherein the life of the blade or cutting edge of the blade is materially prolonged. By the construction of the invention the blade operates under an ideal condition so that the edge is maintained, thus prolonging the life of the blade and assuring satisfactory operation over a long period of time.

Another object of my invention is to provide a razor blade construction whereby the cutting edge of the blade is lubricated as the razor is operated, thus causing the cutting action to be highly efficient and eliminating the harshness often experienced with razors. With the construction of the present invention the cutting edge is always kept wet so that the edge of the blade itself works in the presence of a liquid or moist condition which lubricates it while the lather at the point where the cutting action is taking place is wetted

to have the desired softening action on the beard.

Another object of the present invention is to provide an attachment for a conventional or ordinary safety razor construction operable to increase the efficiency and improve the action of the razor. The present invention provides a water-carrying device applicable to an ordinary razor construction, which carrier may be made to act in an ordinary or common safety razor as an attachment thereto.

The various objects and features of my invention will be fully understood from the following detailed description of typical preferred forms and applications of the invention, throughout which description reference is made to the accompanying drawing, in which:

Fig. 1 of the drawing is a perspective view of a common or popular type of safety razor embodying the construction of my invention. Fig. 2 is an enlarged detailed transverse sectional view of the razor construction shown in Fig. 1, being a view taken by line 2—2 on Fig. 1. Fig. 3 is a perspective view of the water carrier provided by my invention and which is incorporated in the razor, as shown in Figs. 1 and 2, showing it detached from the other parts of the construction. Fig. 4 is a perspective view of another type of razor construction showing the present invention embodied therein, the parts being opened out to illustrate their arrangement and relationship. Fig. 5 is a sectional view similar to Fig. 2 illustrating the form of the invention shown in Fig. 4 and being a view taken substantially as indicated by line 5—5 on Fig. 4. Fig. 6 is a view showing the water carrier employed in Figs. 4 and 5, showing it detached from the other parts of the construction.

The construction of the present invention, and more specifically the water carrier provided by the present invention, is applicable, generally, to safety razors, that is, it may be incorporated in or applied to the usual forms or types of safety razors. For purpose of example I have chosen to illustrate the invention applied to or incorporated in two typical and common forms of safety razors but I do not wish to thereby have it understood that the invention is limited to these particular situations.

In the form of the invention illustrated in Figs. 1 to 3, inclusive, the razor proper includes, generally, a body 10 which serves to support the razor blade 11, a retainer 12 which acts to clamp the blade to the body, and a handle 13 projecting from the other parts to be readily grasped by the user.

The body 10 of the razor serves, primarily, as a support or carrier for the blade. In the particular case under consideration the blade 11 is a double-edged rectangular blade commonly used in safety razors, and the body, to accommodate such blade, is a substantially rectangular element corresponding generally in size and shape to the blade, although it is somewhat wider than the blade so that its longitudinal edges project slightly beyond the cutting edges 14 of the blade. The longitudinal edges or edge portions of the body 10 are provided with notches 15 which are uniformly spaced and extend into the body at right angles to the edge, leaving a plurality of teeth-like parts 16. In accordance with conventional safety razor construction the edge portions of the body or, in other words, the toothed portions thereof, are formed so that the teeth present a convex or curved surface 17 immediately ahead of the cutting edges 14, the construction being such that the teeth, generally, curve forward from the cutting edges as is clearly shown in Fig. 2 of the drawing.

The blade 11 being the common type of safety razor blade, with its longitudinal edges 14 sharpened, is arranged on the body 10 so that the edges occur immediately behind the fingers 16.

The retainer 12 is in the form of a clamp which bears on the outer side or back of the blade 11 so that its edges 14 are in proper relation to the toothed edge portions of the body. The construction provides means for securing the retainer in place so it properly holds the blade. In the form of the invention under consideration the mounting means for the retainer involves a stem 20 projecting from the retainer 12 to pass through an opening 21 in the blade, an opening 22 in the body and into a threaded opening 23 in the handle 13. The portion of the stem which enters the threaded opening 23 is threaded so that when the handle is rotated onto the stem it serves to draw the stem through the body and thus draw the retainer 12 against the blade.

In the particular construction illustrated the retainer 12 has spaced guide lugs 24 projecting from it at either side of the stem 20 which lugs pass through openings in the blade and are guided by openings 25 in the body. This construction serves to keep the retainer properly oriented relative to the blade and holds the blade in place as the handle is tightened onto the stem.

The general construction thus far described is characteristic of one common type of safety razor.

In accordance with my present invention I provide a water carrier A in connection with the parts hereinabove described, and I locate the carrier so that it serves to keep the cutting edges of the blade wetted or lubricated. The carrier A which is the distinct, novel element of the present invention, is formed of a material or is of such nature as to carry or hold a substantial quantity of water. In practice I have found it most advantageous to form the carrier A of a fine grade of synthetic rubber sponge. In the case under consideration the carrier or sponge is formed as a rectangular body corresponding, generally, to the shape of the blade 11. In the particular case illustrated the sponge may be of the same length as the blade but is slightly narrower than the blade so that it does not overhang or interfere with the cutting edge portion thereof. An opening 30 is provided in the

sponge to pass the stem 20 and side openings 31 are provided to pass or accommodate the lugs 24.

When the sponge is formed as above described it is suitable for arrangement between the blade 11 and the body 10 of the structure above described, and is in the nature of an insert.

In the usual razor construction there is some clearance between the body and the blade intermediate the edge portions of the construction. However, in accordance with my invention I prefer, when making a razor to carry out the invention to provide definite recesses 35 longitudinally in the blade-facing side of the body inward of the toothed edge portions, as will be apparent from Figs. 1 and 2 of the drawing. By thus recessing the body the construction will accommodate a sponge that is comparatively thick or has considerable body and thus operates to hold a substantial quantity of water.

Further when constructing the razor to carry out the present invention the notches 15 provided in the edge portions of the body are extended deep into the body from the edges so that they extend to points well into the recesses 35 and thus the notches are in full communication with parts of the sponge which are thick and thus have considerable capacity.

From the foregoing description it will be apparent how the water carrier or sponge A provided by the present invention, as shown in Fig. 3, may be incorporated in the razor construction as shown in Figs. 1 and 2, so that it occurs between the body and the blade. In use the razor assembled as shown in Figs. 1 and 2 is dipped in water or is thoroughly wetted, with the result that the water carrier A becomes laden with water. The carrier or sponge A will readily absorb a substantial quantity of water and, although it may be in the form of a wafer when dry and initially installed, it quickly absorbs water and swells to occupy the entire space provided between the blade and body.

As the razor is used the water drains from the sponge keeping the cutting edge portion of the blade wet and thoroughly lubricated. The deep notches 15 serve to carry the water from the sponge to the edge. With a supply of water thus delivered to the cutting edge the edge stays moist or lubricated during its cutting action and the cuttings or hair removed by the blade instead of clogging are washed or flushed away, with the result that the blade or edge stays clean and is maintained in condition to cut effectively. Should the cuttings lodge in the construction they can be flushed out just as they are in the ordinary razor. However, in practice it has been found that with the water carrier present in the construction the necessary cleaning of the razor is reduced to a minimum.

In the form of the invention shown in Figs. 4, 5 and 6 the retainer 12^a instead of being detachable from the body, as it is in the case above described, is hinged to the body through suitable hinge connections at 40. The blade in this type of razor has a single cutting edge 14^a and has an inner edge with a binding 41. The body 10^a has a single forward edge portion with a plurality of notches 15^a. Ears 50 are provided at the ends of the blade as stops for the blade. The body 10^a where it faces the blade is preferably recessed or depressed at 35^a so there is a substantial space between the body and the blade to accommodate the carrier A^a. The openings 15^a preferably extend a considerable distance into the body so that they communicate with a portion of the

structure where the carrier A' has a considerable thickness.

The carrier A' is in this case, as in the other form of the invention, preferably a sponge and is shaped to fill the space between the body and the blade. A retaining strip 60 may be provided to extend longitudinally between the edge portions of the body over the sponge A' to retain it in position in the cavity portion of the body. In this form of the invention the sponge is shown extended to a point very close to the cutting edge of the blade. In practice the sponge may be extended to the immediate vicinity of the blade so that it actually serves to cooperate with the body in guarding or shielding the cutting edge so that it does not cut the user.

In the form of the invention shown in Figs. 4 and 5 the body has an extension 70 to which the handle 13^a is attached and various other features common to safety razor construction are included in the device.

From Figs. 4 and 5 it will be apparent how the retainer 12^a can be swung to an open position, as shown in Fig. 4, allowing the blade 11^a and the sponge A' to be arranged in or removed from the body 10^a at will. When the device is in operation the sponge A' and the blade are arranged as shown in Fig. 5 and the retainer 12^a is in a closed position where its outer end portion bears down against the blade holding the blade in place, the blade being effectively held in the desired location against the ears or stops 50.

In the form of the invention just described the sponge acts as it does in the case illustrated in Figs. 1 and 2 of the drawing. When in use the razor is thoroughly wetted so that the sponge is loaded with water, and as the shaving operation progresses the water drains from the sponge keeping the cutting edge of the blade wet, lubricated and flushed clean.

Having described only typical preferred forms and applications of my invention, I do not wish to be limited or restricted to the specific details herein set forth, but wish to reserve to myself

any variations or modifications that may appear to those skilled in the art or fall within the scope of the following claims.

Having described my invention, I claim:

5. A razor of the character described including, a body notched to form a toothed edge, a blade arranged over the body so its edge is at the toothed edge of the body, a retainer holding the blade at the body, and an element inserted between the body and blade to carry water and engaging the notched portion of the body.
10. A razor of the character described including, a body, a blade arranged over the body, means orienting the blade in a predetermined position relative to the body, a retainer holding the blade at the body, and an element inserted between the body and blade to carry water and oriented by said means.
15. A razor of the character described including, a body, a blade arranged over the body, parts engaged between the blade and body orienting the blade relative to the body, a retainer holding the blade at the body, and an element inserted between the body and blade to carry water and oriented by said parts to be oriented relative to the blade and body.
20. A razor of the character described including, a body notched to form a toothed edge, a blade arranged over the body so its edge is at the toothed edge of the body, a retainer holding the blade at the body, and an element inserted between the body and blade to carry water, there being a recess in the body for the reception of the element, which recess extends to the notched portion of the body.
25. An insert for a razor including a substantially rectangular thin sheet of sponge to supply water to the blade of the razor.
30. An insert for a razor including a substantially rectangular thin sheet of sponge to supply water to the blade of the razor, the sheet corresponding generally to the blade of the razor to be retained like the blade is retained.
35. HYMAN SCHWARTZ.
